DESIGN FOR A LOOP FOR LIGHTING-FIXTURES.

57,585.

Specification for Design. Patented Apr. 26, 1921.

Application filed September 2, 1920. Serial No. 407,811. Term of patent 3½ years.

To all whom it may concern:

Be it known that I, FRED E. CHAMBERS, a citizen of the United States, residing at Coldwater, in the county of Branch and State of Michigan, have invented a new, original, and ornamental Design for a Loop for Lighting-Fixtures, of which the following is a specification, reference being had to the accompanying drawing, forming part thereof.

Figure 1 is a front elevation of a loop for lighting fixtures embodying my new design. Fig. 2 is a side elevation of the same.

I claim:

The ornamental design for a loop for lighting fixtures, as shown.

FRED E. CHAMBERS.
